FLUID OPERATED MOTOR

Thomas F. Stacy, Piqua, Ohio, assignor to The French Oil Mill Machinery Company, Piqua, Ohio

Application April 26, 1938, Serial No. 204,375

14 Claims. (Cl. 60—52)

This invention relates to fluid operated motors such as hydraulic presses, and more particularly to the mechanism for controlling the reciprocations of a ram element.

One object of the invention is to provide improved controlling means for a fluid operated motor, with which objectionable shock to the motor and system through high pressures will be eliminated, particularly when the system is operated to reverse the direction of travel of the ram element after it reaches a desired forward position; with which jumping of the ram element during a working stroke and upon a sudden decrease in resistance to its forward movement is reduced until it is unobjectionable; with which speedy preliminary advance movement of the ram element will not be materially restricted; and which will be relatively simple, practical, dependable, rapid in operation, and inexpensive.

Another object of the invention is to provide an improved method of operation of ram elements in a fluid actuated motor, with which objectionable shocks to the system upon reversals in the direction of travel of the platen will be eliminated; with which rapid advance of the ram element will be possible until substantial resistance is encountered; with which objectionable jumping of the ram element during a working stroke, upon a sudden decrease in resistance to its forward movement, will be prevented; with which the direction of travel of the ram element may be changed at any point in either forward or retracting movements; and which will be relatively simple, practical, and require a minimum of expensive equipment and a minimum of changes in existing systems of control.

Another object of the invention is to provide improved means for controlling the activity of the movable ram element of a fluid actuated motor, with which objectionable shocks to the fluid system and apparatus will be prevented at the stoppage of the forward movement of the ram element at any points in its working and retraction strokes; with which rapid closing of the ram element may be obtained, but with resistance to jumping of the ram element if the resistance to its working stroke is suddenly decreased; and with which the controlling valve may be either power or manually operated, or both.

Another object of the invention is to provide improved means for controlling a fluid actuated motor, with which smoothness and rapidity of operation of the motor may be obtained, and which will be relatively simple, dependable, and inexpensive.

Other objects and advantages will be apparent from the following description of some embodiments or examples of the invention, and the novel features will be particularly pointed out hereinafter in connection with the appended claims.

In the accompanying drawings:

Fig. 1 is a schematic diagram of portions of a fluid actuated motor having a controlling system therefor constructed in accordance with this invention;

Fig. 2 is a somewhat similar schematic diagram, but illustrating slight modifications in the system, and

Fig. 3 is a diagram similar to Fig. 1 but with further modification thereof.

In the embodiment of the invention illustrated in Fig. 1, the fluid actuated motor includes a ram element 1 having a piston 2 reciprocating in a ram casing 3, with a main cylinder 4 at one side of the piston to force the ram element forwardly in a working stroke and a pull-back cylinder 5 at the opposite side of the piston 2 for retracting the ram element 1. These parts are typical of a fluid actuated motor, and in many cases the pull-back cylinder is in a separate housing from the main cylinder 3 but connected to the ram element 1, and it will be understood that the invention relates to the actuation of the ram element in one direction by pressure in a main cylinder and in the opposite or retracting direction by a pull-back cylinder, whether the main cylinder and pull-back cylinders operate on the same or different pistons connected to the ram element.

Any source of operating fluid under pressure may be employed, but for convenience I have illustrated the source to be a pump 6 which draws liquid from a suitable reservoir 7 through a pipe 8, and delivers it under pressure through a pipe 9. Any suitable type of pump may be employed, the one illustrated being of the variable displacement or variable delivery type, in which any slippage of liquid is returned by pipe 10 to the reservoir 7. A light pressure opened check valve 11 of any suitable construction is connected in series in the pipe 9 between the pump 6 and the controlling or operating valve 12. The valve 12 includes a casing with a valve chamber 13 in which reciprocates a valve element 14. The valve element 14 is provided with a pair of spaced lands 15 and 16 which are of a size to fit closely with the wall of the chamber 13 and cooperate with ports in the wall of chamber 13 in a manner which will be described presently.

55 A helical compression spring 17 is compressed

between one of the lands, such as 16, and an end wall 18 of the housing 12, and urges the valve element 14 in a downward direction in Fig. 1. The pipe 9 opens into the valve chamber 13 through a port 19 which is between the lands 15 and 16 when the valve element 14 is in an intermediate position, which is the position shown by full lines in Fig. 1. A pipe 20 opens into the valve chamber 13 through a port 21 aligned with the land 16 when the valve element 14 is in said intermediate position, and also is connected to the main cylinder 4. Another pipe 22 opens into the chamber 13 through a port 23 which is aligned with the land 15 when the valve element 14 is in its said intermediate position. The land 15 is of a width which normally closes this port 23, so as to close communication to that end of the pipe 22.

The land 16 is bevelled on opposite sides, as shown in Fig. 1, so that when it is aligned with the port 21 there will be clearance between the land and the port 21, and fluid in the chamber 13 received through the port 19 and pipe 9 may pass around the land 16 to the upper end of the chamber 13 as well as pass to the pipe 20. An exhaust pipe 24 opens into the upper end of the chamber 13 through a port 25, and in turn is connected to the pipe 10 leading back to the reservoir 7. The lower end of the chamber 13 also has a port 26 opening into the pipe 24. The pipe 22 is connected to the pull-back cylinder 5, but one zone of it is sub-divided into three branch pipes 22a, 22b and 22c which are all in parallel to one another. The branch 22a contains a free check valve 27 which opens freely to pass fluid through the pipe 22 toward the pull-back cylinder 5 and automatically closes to prevent reverse flow.

In the branch pipe 22b I have included a meter valve or adjustable valve 28 which may be adjusted to pass a selected and regulatable amount of operating fluid in both directions therethrough, which would be both toward and from the pull back cylinder 5. In the branch 22c I have included a heavy pressure release valve 29 which opens to pass fluid leaving the pull-back cylinder 5 when the pressure on the escaping fluid exceeds a predetermined pressure, and closes automatically to prevent flow of the operating fluid therethrough towards the cylinder 5. This pressure release valve 29 may be adjusted by varying the spring pressure on its valve element so as to vary the pressure that must be created in the cylinder 5 before it will lift the valve element and pass operating fluid therethrough from the cylinder 5. This valve 29 is in a sense a safety valve, and ordinarily becomes effective only when the fluid pressure in the cylinder 5 becomes excessive, such as might happen, for example, if someone should inadvertently close off the valve 28 entirely or largely so.

A pipe 30 leads from the reservoir 7 to the cylinder 4, and it contains in series therein a pilot operated, free check valve 31. This check valve opens freely to pass liquid from the reservoir 7 to the main cylinder 4, but normally closes automatically to prevent all reverse flow. The reservoir 7 should preferably be elevated above the cylinder 4 to facilitate free flow of oil from the reservoir into the cylinder during the prefill stroke of the ram 1. When fluid pressure is supplied to the pilot cylinder 32, however, it forces the pilot piston 33 upwardly against the action of the pilot spring 34, so as to engage and force open the movable valve element 35 of the check valve 31, and thus allow fluid to flow from the cylinder 4 through the pipe 30 back to the reservoir 7. The

7 pilot cylinder 32 is connected by a pipe 36 to the pipe 22 which leads to the pull-back cylinder 5 at a point between the three branch circuits 22a, 22b and 22c and the valve 12.

5 The valve element 14 extends outwardly through one end of the valve housing 12, and this projecting end has a peripheral notch 37 which may be engaged by the nose 38 of a latch or detent 39, when the valve element 14 is pulled outwardly, which would be upwardly in Fig. 1. A spring 40 acting on the latch 39 urges it in a direction to snap into the notch 37 whenever the valve element 14 is lifted until the notch 37 moves into alignment with the nose 38 of the latch. This projecting end of the valve element 14 also extends into and through a chamber or cylinder 41 of a housing 42, and a piston 43 is mounted for reciprocation on the valve element 14 and in the chamber 41. In fact, the piston 43 extends through opposite walls of the housing 42, with suitable gaskets or packing where it passes through the opposite walls of the housing. The end which passes through the upper wall, in Fig. 1, of the housing 42 is of lesser diameter than the portion which passes through the opposite or lower wall of housing 42. A helical compression spring 44 is compressed between a flange 45 on the outer reduced end of the piston 43 and the housing 42, so as to normally urge the piston 43 upwardly in Fig. 1, that is, to retract the larger end of piston 43 into the chamber 41. The lower end of the piston 43 is bevelled as at 46, so as to act as a cam surface which engages with the latch or detent 39 and cams it into a position to carry its nose 38 out of the notch 37 and release the valve element 14, whenever the piston 43 is forced downwardly sufficiently in Fig. 1.

20 A pipe 47 leads from the pipe 20 to the chamber 41 and it may include therein a freely operating check valve 48 of the type which opens freely to pass fluid through the pipe 47 from the chamber 41 to the pipe 20, and closes automatically to prevent reverse flow. Connected to the pipe 47 at opposite sides of the valve 48, so 45 as to be in parallel with the latter, is a branch pipe 49 having in series therein a pressure relief valve 50 of the type which opens to pass fluid from the pipe 20 to the chamber 41 whenever the pressure in the pipe 20 exceeds a predetermined pressure for which the pressure relief valve 50 is set. This valve 50 closes automatically to prevent reverse flow. The valve element 51 of the pressure relief valve 50 is urged into closed position, for example, by a spring, and the compression of the spring may be varied by the adjustable screw 52 as usual in pressure relief valves. Therefore when the pressure in the cylinder 4 reaches or exceeds a predetermined pressure corresponding to that for which the relief valve 50 is set, this pressure which also exists in the supply pipe 20 will be transmitted to the pipe 47 and will be sufficient to lift the valve element 51 and flow through the branch 49 and then again through the pipe 47 to the chamber 41. The fluid under pressure thus delivered to the chamber 41 will force the piston 43 downwardly against the action of spring 44, and the bevelled nose 46 of piston 43 will engage the latch or detent 39 and cam it into a position to release the valve element 14, whereupon the spring 11 will force the valve element 14 downwardly into and, if or when possible, beyond the intermediate position shown by full lines in Fig. 1.

25 A hand control lever 53 is pivoted at 54 to any suitable support, and an arm of this lever en-

gages beneath a flange or head 55 provided on an adjacent end of the valve element 14, so that when the free end of the lever 53 is pushed downwardly it will force the valve element 14 against the action of spring 17, which will be upwardly in Fig. 1, so that the latch 39 may engage the notch 37 and hold the valve element in that position. When the valve element 14 is latched in this position, the land 16 will be in a position between the ports 21 and 25, and since the land is not then in alignment with either of these ports, it will close communication between those ports, and operating fluid will therefore no longer be able to pass around the periphery or past the edge of the land 16. At the same time the land 15 was carried out of alignment with the port 23 and into a position between the ports 19 and 23. Thereupon the fluid under pressure which is delivered by the pipe 9 to the chamber 13 is free to pass directly from the port 19 across chamber 13 to the port 21, but it will be cut off from reaching the port 25. This fluid reaching the port 21 will pass through the pipe 28 to the cylinder 4 and thus tend to exert a fluid pressure on the piston 2 and cause it to descend and carry the ram element 1 downwardly.

When the land 15 moved between the ports 19 and 23 it uncovered the port 23, and thereupon the ports 23 and 26 were placed in communication with one another through the lower part of the chamber 13. The pipe 22 is thus placed directly in communication with the pipe 24 leading back to the reservoir 7, and any fluid in the pipe 22 may thus pass freely back to the reservoir 7. Fluid from the pull-back cylinder 5 may therefore escape through the pipe 22, meter valve 28, pipe 22, lower part of chamber 13 and pipes 24 and 10 back to the reservoir 7, so that the ram element 1 may descent at a rate depending upon the rate of escape of the operating fluid from cylinder 5 through the valve 28. As the piston 2 descends, the pressure chamber in cylinder 4 will increase in volume more rapidly than the pump can supply operating liquid thereto, and therefore until resistance is encountered by the descending ram element 1, a suction may be created in cylinder 4 which, through the pipe 30, will draw liquid from the reservoir 7 to fill the space vacated by the descending piston 2. It will be understood that the valve element 35 of pilot check valve 34 will open freely to pass this fluid into the cylinder 4.

When the descending piston encounters resistance, the suction in cylinder 4 will stop because the liquid passing through pipe 20 will be sufficient to fill the space vacated by the descending piston, whereupon the valve 35 will close automatically, and continued delivery of operating fluid through the pipe 20 to the cylinder 4 will not only hold the valve element 35 closed but will build up a pressure in cylinder 4. When this pressure increases past that for which the relief valve 50 is set, it will escape past the valve element 51 of valve 50 and reach the chamber 41, and then by forcing the piston 43 downwardly will disengage the latch 39 from the valve element 14 and allow the latter to be shifted back into the intermediate position shown in full lines in Fig. 1. When this occurs the pipe 20 will again be connected through the port 21 with the port 25, and the operating fluid may then escape from cylinder 4 through pipe 20, port 21, upper part of chamber 13, port 25 and pipes 24 and 10 back to the reservoir. At the same time the land 15 again closes the port 23 so that operating fluid

cannot escape from the cylinder 5. Pressure will, therefore, drop in cylinder 4 and the liquid delivered by the pump will be by-passed at no pressure around land 16 through pipes 24 and 10 back to the reservoir.

If the valve element 14 passes the position shown in full lines in Fig. 1, it will carry the land 15 between the ports 23 and 26 so as to cut off communication between the same and to uncover the port 23. The land 16 will similarly be carried into a position between the ports 19 and 21 so as to shut off communication between the same and thereupon the pipes 9 and 22 will be directly connected. When that happens, the pipe 20 will still be connected to the pipe 24 to allow escape of operating fluid from cylinder 4 back to the reservoir 7, and the operating fluid delivered by the pump through the pipe 9 will be conducted across the chamber 13 to the pipe 22 and then will pass partly through the check valve 27 which opens freely to permit this passage and partly through the valve 28 to the pull-back cylinder 5 so as to create a fluid pressure in the latter tending to force the piston 2 upwardly and retract the ram element 1.

Since the effective volume of the cylinder 5 increased by the upwardly moving piston 2 is very greatly less than the rate of decrease in the effective volume of cylinder 4 by the same movement of piston 2, it follows that if the fluid pressure from the pump is delivered to the pull-back cylinder 5 before the pressure in cylinder 4 has fallen sufficiently, unnecessarily high pressures may be created in the pull-back cylinder 5 with the resulting shock to the press or fluid motor and the system. The pressure in the pipe 22 is also communicated through the pipe 36 to the pilot cylinder 32, and tends to open the valve 35 forcibly, but valve element 35 cannot move into open position as yet because of the very high pressure in the cylinder 4 which opposes the opening movement of the valve element 35. I therefore propose to prevent the movement of valve element 14 beyond the intermediate position shown in Fig. 1, so as to prevent the delivery of fluid under pressure to the pull-back cylinder, until the pressure in the main cylinder 4 has fallen to such an extent that the valve element 35 may be immediately opened.

For this purpose an end 63 of valve element 14 extends into a closed chamber 56 where it functions as a piston. Extending into the same chamber 56 is a stop piston 57 which passes in the opposite direction out of the chamber 56 and into another chamber 58 where it carries a substantial head or flange 59, and then has a section of reduced diameter or stem 60 passing outwardly of the chamber 58. A spring 61 is compressed between the housing for chamber 58 and adjustable nuts 62 on the outer end of the stem 60, so as to normally urge the stem 60 downwardly or outwardly and thus tend to retract the stop piston 57 out of the chamber 56 or in a direction away from the end 63 of the valve element 14 which is within the chamber 56. The flange or head 59 of this stop piston 57 which is within the chamber 58, by engagement with the wall of the chamber 58, limits the upward movement of the stop piston to a position such that it engages with the end 63 of the valve element 14 and opposes or blocks further movement thereof under the urge of the spring 61 beyond the intermediate position shown in full lines in Fig. 1. Thus by applying fluid pressure

to the chamber 58 the stop piston 57 may be held in a position to limit the movement of the valve element under the action of its spring 17 to the intermediate position shown, until it is desired to allow further movement of the valve element, and then the lowering of the pressure in chamber 58 will permit the spring 61 to retract the stop piston 57 and allow continued movement of the valve element 14 into the second position in which it connects the pipe 9 to the pipe 22 and starts the retraction of the ram element 1.

The pressure in the chamber 58 is established at the proper time by means of a pipe 64 which leads from the pipe 20 to a valve 65 having three lands 66, 67, and 68 on a movable valve element 69 thereof. A pipe 70 connects the valve 65 to the chamber 58. A pipe 71 connects the chamber of valve 65 to the pipe 22. A spring 72 in the housing of valve 65 acts on the valve element 69 to force it downwardly in Fig. 1 from the position shown in full lines, to the position shown in dotted lines. The valve element 69, however, is connected to a trip rod 73 and it carries a collar 74 which may be in a position to be engaged by the arm 75 on the ram element 1, when the latter reaches a selected position in its retraction or return stroke. The collar 74 is adjustable, such as by means of a set screw in the collar, to different positions along the rod 73 so as to determine, and enable variation in, the position in the return movement of the element 1 at which the arm 75 will engage collar 74 and force it and the valve element 69 up into the position shown in full lines in Fig. 1.

When the valve element 69 is held in its upper position, as shown in Fig. 1, the pipe 71 will be connected by the space between the lands 66 and 67 to the pipe 70, and thus the chamber 58 will be subjected to the pressure in the pipes 71 and 22 and the cylinder 5. Since the pipe 22 is closed at the port 23 by the land 15, the weight of the piston 2 and the ram element 1 will place the fluid confined in cylinder 5 under pressure which will be transmitted through the pipes 22, 71 and 70 to the chamber 58, and will hold the stop piston 57 in the elevated position where it prevents downward movement of the valve element 14 under the action of spring 17. During this time the fluid from pipe 9 will pass idly by the land 16 back to the reservoir, and the element 1 will remain in its upper retracted position.

When the ram element 1 is away from retracted position, however, it releases the collar 74 and the spring 72 shifts the valve element 69 into the dotted line position, at which time the land 66 moves between the openings to pipes 70 and 71 so as to cut off communication between the same, and the land 67 moves downwardly beyond the opening to pipe 64 so that communication will then be established between the pipes 64 and 70 by the space between the lands 66 and 67. At such time, since the pipe 64 is connected to the pipe 20 leading to the cylinder 4, the fluid pressure in the cylinder 4 will pass through the pipes 20, 64 and 70 to the chamber 58 and the stop 57 will be held in its obstructing position shown in Fig. 1. When this pressure lessens sufficiently the piston 57 can descend, allowing valve element 14 to descend and connect pipe 9 from the pump to the pipe 22 running to the return ram chamber 5. When the valve element 14 is moved upwardly, however, so as to uncover port 23, the pipe 22 will be relieved of fluid pressure because the operating fluid is then

free to escape from cylinder 5 through pipes 22 and 24 back to reservoir, and consequently the pressure in the chamber 58 will fall enabling the spring 61 to retract the stop 57.

- 5 To enable power operation of the valve element 14 into latched position, such as when one desires to start a forward stroke of the element 1, the chamber 56 is connected by a pipe 76 to another valve 77 which connects the pipe 76 alternately to one pipe 78 leading to the pipe 10 and thence back to the reservoir, and to another pipe 79 leading to the pipe 9 at a point between the check valve 11 and the pump 6. A spring 80 acting on the valve element 81 of the valve 77 normally urges the valve element 81 upwardly into the position shown in full lines in Fig. 1, at which time the pipe 76 is connected to the pipe 78, which relieves the chamber 56 of all fluid pressure. A land 82 on the valve element 81 obstructs communication between the pipes 76 and 79. A solenoid 83 is connected to the valve element 81 so as to operate the same against the action of the spring 80, and this solenoid is energized at will from line wires L¹ and L² under the control of a switch 84. Thus, when the solenoid 83 is energized following closing the switch 84, the valve element 81 will be pulled downwardly so as to place the land 82 between the openings to pipes 76 and 78 and obstruct communication between them, and by moving beyond the opening to passage 76, it will connect pipes 76 and 79. Thereupon fluid from the pipe 9, between the pump 6 and the check valve 11, will pass through pipes 79 and 76 to the chamber 56, and by exerting pressure on the end 63 of the valve element 14, will force the latter upwardly to a position in which it is then latched automatically by the latch or detent 39. The pressure in chamber 56 may tend to force the stop piston 57 downwardly, but this does no harm and it is only momentary.

The pressure-opened check valve 11 serves a dual purpose. It creates enough back pressure in the portion of pipe 9 leading to the pump to provide a continuous source of fluid under pressure to supply pipe 79 with operating fluid, and it also prevents the feeding of oil from the press back to the pump.

If the press is open and idle and if the pump and motor should be stopped, then the press ram 50 will gradually drop down, due to leakage, and as soon as it has dropped down far enough, valve 65 will operate, which will allow the rod 73 to drop and will connect chamber 58 through the pipes 64 and 20 to the main cylinder 4. This will allow the valve stem 57 to drop, and pipe 22 will then be connected through the ports 23 and 19 to pipe 9. The weight of the press will then feed the oil back through the pipe 9, and without the check valve 11 in this pipe 9, the pump would act as a motor and run backward, and the press ram would drop rapidly.

When the valve element 14 is latched in the above manner, it initiates a downward movement of the ram element 1 as previously explained. As 65 soon as the element 1 starts downwardly it releases collar 74, and rod 73 then falls under the action of spring 72, and the valve element 69 is shifted into the dotted line position so as to connect the pipe 64 to the pipe 70 and thus to the chamber 58. During the initial downward movement of the piston 2, a suction will be created in the cylinder 4 which is filled by liquid from the reservoir through pipe 30, and thus there will be little or no pressure created in the chamber 58. As soon as the element 1 encounters sub-

stantial resistance, however, the valve 31 closes and fluid pressure begins to build up in cylinder 4. This pressure is then communicated through the pipes 20, 64, valve 65 and pipe 70 to the chamber 58 and the pressure in this last chamber forces the stop piston 57 into its upper or obstructing position shown in full lines in Fig. 1. It remains in that position as limited by the flange or head 59, but out of contact with the end 63 of valve element 14 because the latter is in its upper or latched position.

When the valve element 14 is released by the pressure in chamber 41 of the unlatching device, the valve element 14 will be shifted endwise by spring 17 until it engages the stop piston 57 and is stopped in the intermediate position shown by full lines in Fig. 1. This closes off the pipe 22 at port 23, so that no fluid can escape from cylinder 5, and the pipe 20 is then connected around land 16 to the pipe 24, so that by the escape of fluid from cylinder 4 through pipes 20 and 24 back to the reservoir, the pressure in cylinder 4 will fall. Since the arm 75 is still in a lower position where it is free of collar 74, the valve 65 will still keep the pipe 64 connected through the pipe 70 to the chamber 58 and thus maintain the same fluid pressure in chamber 58 as exists in cylinder 4. When the pressure in cylinder 4 has fallen, however, to a relatively low pressure, the pressure in chamber 58 will also have fallen correspondingly and spring 61, aided by the spring 17, will then retract stop 57 and allow the valve element 14 to follow under the pressure of spring 17 until it moves into the reversing position in which the land 15 is between ports 23 and 26 and the land 16 is between ports 19 and 21.

When this happens the pipe 9 will be connected to pipe 22, so as to deliver fluid under pressure to the cylinder 5 to start a retraction of the piston 2, and pipe 20 will be connected to the return pipe 24, so that the fluid displaced from the cylinder 4 by the piston 2 may flow freely back to the reservoir 7. Since more liquid is displaced from cylinder 4 than is delivered to the cylinder 5, and work must be done to retract the ram element 1 and piston 2, pressure will build up in pipe 22 and this pressure entering pipe 36 will force open the valve element 35 and permit flow of the fluid from cylinder 4 also through pipe 30 and valve 31 back to the reservoir 7, thus making two paths for escape of fluid from cylinder 4 and making possible a more rapid return movement of the piston 2. As the piston 2 approaches its upper limit of movement, the arm 75 will reengage the collar 74 and shift the valve element 69 back into the position shown in full lines in Fig. 1 and thus break the connection between pipes 64 and 70 and reestablish the connection between pipes 71 and 70, thus returning the chamber 58 to the pressure existing in the pull-back cylinder 5.

This pressure of the pull-back cylinder 5 which is received directly from the pipe 9 and the pump, and which is transmitted to the chamber 58, will force the stop piston 57 back into its obstructing position and will forcibly shift the valve element 14 back into the intermediate position shown in full lines in Fig. 1, stop the further upward movement of the piston 2, and allow the fluid under pressure from the pipe 9 and pump 6 to circulate past the land 16 to pipe 24 and then back to the reservoir 7. The parts remain in these positions until another forward movement of the ram element 1 is initiated, either by operating the hand lever 53 to release the valve

element 14, or by closing the switch 34 to cause a hydraulic operation of the valve element 14 back into latched position.

If, at any time while the valve element 14 is latched and the piston 2 is descending, one desires to stop the further forward movement of the piston 2 and return it, it is merely necessary to operate the hand-controlled lever 53 in the opposite direction so that the end beneath the flange 55 will engage with the flange 45 on the unlatching piston 43, and force the same along the valve element 14 to disengage the detent or latch 39 and release valve element 14, whereupon the spring 17 will operate the valve element 14 to cause a return movement of the piston, as above explained.

After a tripping of latch 39 by pressure in chamber 41, it is advisable to reduce the pressure in chamber 41 quickly so that the valve element 14 can again be relatched, and immediately if desired. The valve 48 will quickly release this pressure after the pressure in the main cylinder has fallen sufficiently, but since the fall of pressure in cylinder 4 is not instantaneous, a bleeder 88 may be provided between the chamber 41 and pipe 30 leading to the reservoir 7, so that fluid may escape from chamber 41 either by valve 48 or bleeder 88 or by both. Only one of these paths of escape from chamber 41 is necessary, but both may be used if desired. The bleeder 88 must be sufficiently small so that flow of fluid through the valve 50 will be greater than the rate of escape through the bleeder and create a pressure in chamber 41 sufficient to operate piston 43.

While, as explained above, the pump 6 may be of any suitable type, even a fixed stroke type, I have illustrated it as of the pressure holding, variable displacement type which is particularly advantageous in this type of system. As usual in this type of pump, a pipe 86 connects the pipe 9 to the usual cylinder 87 in which reciprocates piston 88 that acts upon a shifting lever 89 that varies the rate of delivery of the pump 6. A spring 90 is confined on a rod 90a between a collar 90b on the rod and a U-shaped arm 90c hinged at 90d to the lever 89. The rod 90a extends through a wall 90e and carries a nut 90f. Thus, by turning the nut 90f the compression of spring 90 may be varied.

The spring 90, acting on the arm 90c, urges the lever 89 in a direction to throw the pump on to full stroke or maximum delivery, and forces the piston 88 inwardly into the chamber 87. Since the chamber 87 through the pipe 86 is responsive to the pressure in the pipe 9, it follows that when the working pressure in the main cylinder 4 increases sufficiently to overcome the pressure of the spring 90, the piston 88 will be forced outwardly and will shift the lever 89 and set the pump 6 to a very small delivery, or to neutral or no delivery to hold that pressure. The pump will then continue to operate until the valve element 14 is released to cause a reversal of the ram. When the latch 39 is operated, the valve element 14 is shifted into the intermediate or full line position of Fig. 1, and the fluid delivered by the pump is then by-passed around the land 16 back to the reservoir. The pipe 20 will remain subject to the pressure in the main cylinder 4, and through the pipe 64, valve 65, pipe 70, chamber 58 and pipe 86, the chamber 87 at the pump will also remain subject to the pressure in cylinder 4.

In the foregoing description, reference has been made to vertical movements for various

parts, but this has been done for convenience of reference and to indicate directions of movement, but it will be understood that the parts will perform these relative functions just the same whether arranged in the position shown or disposed in horizontal or other positions, and such positions or movements as are described as either horizontal or vertical, are to be understood as not limiting details of the invention.

Referring now to Fig. 2, a slight modification of the system shown in Fig. 1 is illustrated. Parts in Fig. 2 which correspond to similar parts in Fig. 1 are designated by the same reference characters and will not be further specifically described, but the differences from Fig. 1 will be expressly set forth. Referring now particularly to Fig. 2, a pressure closed valve 91 is included in series in the branch pipe 22b. This valve 91 has a valve element 92 which is urged into open position by a spring 93 so that normally the valve 91 is fully open and the valve 28 then represents the only restriction to fluid flow through the branch pipe 22b. The valve element 92 extends into a closed chamber 94, and the latter is connected by a pipe 95 to the pipe 20. Thus when the pressure in the pipe 20, as communicated through the pipe 95 to the chamber 94, becomes high enough to overcome the pressure of spring 93 it will force the valve element 92 into closed position and thus keep valve 91 closed and shut off all fluid flow through the branch pipe 22b. Hence the valve 91 is pilot closed in response to the pressure in the main cylinder 4.

Since the pressure in cylinder 4 will be relatively low during the descent of the piston 2 until substantial resistance is encountered, the valve 91 will remain open so that operating fluid may escape freely from the pull-back cylinder 5 to the extent permitted by the regulation of the valve 28, but when resistance is encountered by element 1 and the pressure in cylinder 4 begins to build up, the valve 91 will be pressure closed immediately so that substantial back pressure in cylinder 5 will be built up. Then, the operating fluid can escape from cylinder 5 only when its pressure is sufficient to pass the pressure opened relief valve 29. With valve 91 closed, if the resistance to movement of the ram element 1 should be suddenly lessened, the piston 2 and ram element 1 cannot jump ahead materially because of the back pressure in the pull-back cylinder 5. This jumping restriction during a press stroke makes the press or motor particularly applicable for use in blanking operations, such as in the drawing or blanking of metal sheets. Heretofore hydraulic presses have been used very little for blanking operations, because the press ram will come down against the metal to be blanked, the required blanking pressure will be built up, and then as the metal is blanked, this energy must be suddenly released which tends to cause the press ram to jump forward with considerable shock to all the equipment. With this arrangement, however, of creating substantial back pressure in the pull-back cylinder only during the actual drawing or blanking operation, the tendency of the ram to jump forward when the metal is blanked is substantially prevented or reduced to such an extent that it is unobjectionable, yet since the valve 91 is opened while the press is closing, there is no material decrease in the speed of operation of the press as a whole.

In order to prevent overrunning or overstroke

of the ram element, I may also provide a limit device for reversing the motor which will now be described. A valve device 96 is disposed in position for operation by the arm 75 or other suitable part of the ram element 1 when the desired maximum limit of movement of element 1 is reached. For example, the valve element 97 of valve 96 extends out of the valve housing 98 and terminates in a rod 99 along which the arm 75 moves. A collar 100 is secured on the rod 99 for adjustment into different positions therealong where it may be engaged by the arm 75. A spring 101 acts on the valve element 96 to hold it normally in its upper position, and when the arm 75 engages collar 100, continued descent of the element 1 will force the rod 99 downwardly against the action of spring 101. The chamber of valve 98 is connected by a pipe 102 to the pipe 79 which communicates with the pipe 9, so that fluid under pressure normally delivered by the pump 6 will be transmitted to the chamber of the valve 98 at a point between the lands 103 and 104 on the valve element 97.

A pipe 105 extends from the pipe 47 to the chamber of valve 98 at a point below the land 103 when the valve element is in its upper position shown in full lines in Fig. 2. The land 103 thus normally interrupts communication between the pipes 102 and 105. When the arm 75 engages collar 100 and depresses the valve element 97, the land 103 moves beyond the opening to pipe 105 before the land 104 reaches the opening to pipe 102 and thus communication will be immediately established from the pipe 102 to the pipe 105, and thence through pipe 47 to chamber 41 of the housing 42. This transmits fluid under pressure directly to the chamber 41 where it actuates the latch-tripping piston 43 to disengage latch 39, the same as described in connection with Fig. 1 when the fluid under pressure was delivered to the chamber 41 directly from pipe 20. Thus the valve 98 is a position responsive reversing control which acts in addition to the pressure responsive control device 50, and if the pressure responsive device does not cause reversal automatically when a desired pressure has been built up, the device will be reversed by this position responsive device, provided that the element 1 travels the necessary further distance. The purpose of this combination of position and pressure reversing control is a perfectly logical one from an operating point of view as well as from a safety point of view. If the press is used for blanking operations the positioning control may be used, and the same press with different dies for, say, a forming operation, can be operated with a pressure reversing control. The press can be made with both controls and both controls can remain operative.

When the press is used for blanking operations, the pressure responsive device is not set as the reversing medium because of the fact that the blanking pressure must be built up until the blank is formed, at which time the resistance pressure falls rapidly and somewhat further movement of the ram is desired before reversal. By adjusting the collar 100 along the rod 99, the point in the travel of the ram element 1 at which the reversal takes place may be varied. The operation is otherwise the same as described in connection with Fig. 1 and need not be repeated.

In the embodiment of the invention shown in Fig. 3, the construction is the same as in Fig. 1, except that I have illustrated a different means

for holding the valve element 14 in the position it occupies in causing an advance of the ram element 1, and for releasing it in response to pressure in the main cylinder 4. Those parts of Fig. 3 which are the same as in Fig. 1 are given the same reference characters. In Fig. 3 the pipe 47 is removed from the pipe 20 and the valves 48, 50, bleeder 85, the latch 39 and the latch tripping mechanism are all removed. In place thereof, a pressure responsive switch 106 is connected by a pipe 107 to the pipe 20. The switch 106 is connected in series in the circuit of the solenoid 83, and is of the snap or toggle type, so that when the pressure on the switch exceeds a predetermined pressure, it will automatically snap into open position and remain open until restored manually or by some other means. Such a switch is shown diagrammatically, and for the purpose of simplicity it includes a snap plate 108 which is disposed in flexed condition between two abutments 109 so as to snap between the positions shown by full and dotted lines. The plate 108 may carry a contact 110 which engages a contact 111 on a leaf spring 112, and the movement of spring 112 toward plate 108 is limited by a stop 113.

When the plate 108 is in the position shown in dotted lines, its contact 110 engages the contact 111 on spring 112 and forces the latter slightly away from stop 113. A piston 114 operating in cylinder 115 is disposed in a position to engage the plate 108 and push it through dead center position and cause it to snap into the full line position. The piston 114 is normally retracted by a spring 116, and compression of the spring 116 may be adjustable in any suitable manner so as to vary the pressure at which it may be overcome and allow the operation of piston 114. When the pressure on the pipe 20 exceeds a predetermined pressure for which the spring 116 is set, this pressure which is transmitted through pipe 107 to chamber 115, will force the piston 114 in a direction to cam the plate 108 from the dotted line position past dead center position and cause it to snap into the full line position.

During this movement the contacts 110 and 111 will remain in contact until the spring 112 engages stop 113, which will be just after the plate 108 has passed dead center position and has started to snap into the full line position. Thus, we will have a rapid separation of contacts 110 and 111 of the switch to prevent arcing. A push button 117 is mounted in position to cam the plate 108 from the full line position to the dotted line position, when it is desired to set the pressure operated switch for operation. The spring 112 is connected by a wire 118 to one end of the solenoid 83 and the other end of solenoid 83 is connected by wire 119 to line wire L². The plate 108 is connected by wire 120 to a manually operated switch 121, which remains in either open or closed position into which it is moved, and the latter is connected to the line wire L¹.

In operation, one starts the press by first closing the switch 121, which remains closed. One then pushes button 117, which forces plate 108 into dotted line position where it closes the circuit through solenoid 83. Solenoid 83 operates valve 77 to shift valve element 14 from the position shown in full lines in Fig. 1, against the action of spring 17 into the position in which it starts an advance movement of piston 2. The plate 108 remains in circuit-closing position and thus the solenoid 83 will maintain the valve 77

in a position to keep the valve 14 in the position in which it causes an advance of the piston 2, when the pressure in pipe 20 has reached a predetermined pressure, for which the pressure-responsive switch is set, the piston 114 of the switch 106 will become active and cam the plate 108 to open the circuit through solenoid 83. This de-energizes solenoid 83 and the valve 77 is then operated to release the valve element 14, whereupon the spring 17 shifts it into the full line position of Fig. 1, momentarily until the pressure in the main cylinder falls, and then shifts the element 14 to cause the retraction of piston 2. Piston 2 is then returned automatically to retracted position and stopped in the manner explained in connection with Figs. 1 and 2.

To start the press for another advance movement, it is merely necessary to again press the button 117 and cam the plate 108 back into circuit-closing position where it remains until operated, by pressure in pipe 20, back into open circuit position. If one desires to stop the advance of the piston 2 before the pressure in the pipe 20 has reached that for which the pressure-responsive switch is set, it is merely necessary to open the switch 121, which will de-energize solenoid 83 and stop the advance, and cause the return of the piston 2 in the same manner as with the opening of the circuit of the solenoid 83 by the pressure-responsive switch. To start another advance of piston 2, one then merely closes switch 121 and the piston 2 will again advance because the circuit is closed at the pressure-responsive switch and then when the pressure again reaches that for which switch 106 is set, the latter will reverse the press, as above explained.

It will be understood that various changes in the details which have been herein described and illustrated in order to explain the nature of the invention may be made by those skilled in the art within the principle and scope of the invention, as expressed in the appended claims.

I claim as my invention:

1. In a fluid operated motor, a main cylinder, a pull-back cylinder, a ram element operated in opposite directions by fluid pressures in said cylinders, means for supplying operating fluid under pressure to each cylinder and releasing fluid from the other cylinder, alternately, to cause reciprocation of said element, means responsive to pressure in said main cylinder for automatically restricting the escape of fluid from the pull-back cylinder whenever the pressure in the main cylinder is above a predetermined pressure, and freely passing the escaping liquid while the pressure in the main cylinder is below said predetermined pressure, means responsive to the pressure in said main cylinder for controlling said fluid supplying means to cause the retraction of said element by said pull-back cylinder after a predetermined pressure in the main cylinder has been reached, and means also controlling said fluid supplying means for causing the delivery of operating fluid to the pull-back cylinder to retract said element whenever said element reaches a predetermined position in its travel under the action of the main cylinder.

2. In a fluid operated motor, a main cylinder, a pull-back cylinder, a ram element operated in opposite directions by fluid pressures in said cylinders, a source of operating fluid under pressure, an operating valve having its movable valve element shiftable into three different positions, connections between said source, said valve and

said cylinders by which said valve connects said source to the main cylinder and the pull-back cylinder to exhaust whenever said valve element is in one position, by which the valve element connects said source to the pull-back cylinder and said main cylinder to exhaust when said valve element is in another of its positions, and by which it cuts off escape of operating fluid from said pull-back cylinder, prevents delivery of fluid under pressure from said source to said main cylinder and relieves the pressure on the fluid in the main cylinder when said valve element is in an intermediate position, and means responsive to the pressure in said main cylinder for preventing movement of said valve element beyond said intermediate position into said another position while the pressure in said main cylinder exceeds a predetermined pressure, and for automatically releasing said valve element for movement into said another position as soon as the pressure in said main cylinder falls below said predetermined pressure.

3. In a fluid operated motor, a main cylinder, a pull-back cylinder, a ram element operated in opposite directions by fluid pressures in said cylinders, a source of operating fluid under pressure, an operating valve having its movable valve element shiftable into three different positions, connections between said source, said valve and said cylinders by which said valve connects said source to the main cylinder and the pull-back cylinder to exhaust whenever said valve element is in one position, by which the valve element connects said source to the pull-back cylinder and said main cylinder to exhaust when said valve element is in another of its positions, and by which it cuts off escape of operating fluid from said pull-back cylinder and prevents delivery of fluid under pressure from said source to said main cylinder when said valve element is in intermediate position, and means responsive to the pressure in said main cylinder and rendered effective by said pressure operated element when the latter is away from a selected retracted position, for preventing movement of said valve element from said intermediate position into said another position where it would cause delivery of fluid under pressure to said pull-back cylinder, until the pressure in said main cylinder has fallen below a predetermined pressure.

4. In a fluid operated motor, a main cylinder, a pull-back cylinder, a ram element operated in opposite directions by fluid pressures in said cylinders, a source of operating fluid under pressure, a reciprocating operating valve having its movable valve element shiftable endwise into three different positions, connections between said source, said valve and said cylinders by which said valve connects said source to the main cylinder and the pull-back cylinder to exhaust whenever said valve element is in one position, by which the valve element connects said source to the pull-back cylinder and said main cylinder to exhaust while said valve element is in another of its positions, and by which the valve element cuts off escape of operating fluid from said pull-back cylinder, prevents delivery of fluid under pressure from said source to said main cylinder and relieves the pressure on the fluid in the main cylinder while said valve element is in an intermediate position, means urging said valve element continuously and yieldingly in a direction from said first to said another position, means for holding said valve element in said first position, means responsive to the pressure in said

main cylinder and operable solely when the pressure in said main cylinder exceeds a predetermined pressure for operating said holding means to release said valve element, and means also responsive to the pressure in said main cylinder for preventing movement of said valve element past said intermediate position when released by said holding means until the pressure in said main cylinder has dropped below a predetermined pressure, and then to release said valve element for continued movement into said another position to cause retraction of said ram element.

5. In a fluid operated motor, a main cylinder, a pull-back cylinder, a ram element operated in opposite directions by fluid pressures in said cylinders, a source of operating fluid under pressure, a reciprocating operating valve having its movable valve element shiftable into three different positions, connections between said source, said valve and said cylinder by which said valve connects said source to the main cylinder and the pull-back cylinder to exhaust whenever said valve element is in one position, by which the valve element connects said source to the pull-back cylinder and said main cylinder to exhaust while said valve element is in another of its positions, and by which the valve element cuts off escape of operating fluid from said pull-back cylinder and prevents delivery of fluid under pressure from said source to said main cylinder while said valve element is in an intermediate position, means urging said valve element yieldingly in a direction from said first to said another position, latch means for latching said valve element in said first position, means responsive to the pressure in said main cylinder and operable solely when the pressure in said main cylinder exceeds a predetermined pressure for operating said latch to release said valve element, and means also responsive to the pressure in said main cylinder but controlled by said ram element and effective only when the latter is away from a predetermined retracted position, for preventing movement of said valve element past said intermediate position when released by said latch until the pressure in said main cylinder has dropped below a predetermined pressure, and then to release said valve element for continued movement into said another position to cause retraction of said ram element.

6. In a fluid operated motor, a main cylinder, a pull-back cylinder, a ram element operated in opposite directions by fluid pressures in said cylinders, a source of operating fluid under pressure, a reciprocating operating valve having its movable valve element shiftable into three different positions, connections between said source, said valve and said cylinders by which said valve connects said source to the main cylinder and the pull-back cylinder to exhaust whenever said valve element is in one position, by which the valve element connects said source to the pull-back cylinder and said main cylinder to exhaust while said valve element is in another of its positions, and by which the valve element prevents delivery of fluid under pressure from said source to said main cylinder and relieves the pressure on the fluid in said main cylinder while said valve element is in an intermediate position, means urging said valve element yieldingly in a direction from said first to said another position, latch means for latching said valve element in said first position, means responsive to the pressure in said main cylinder and operable solely when

the pressure in said main cylinder exceeds a predetermined pressure for operating said latch to release said valve element, means also responsive to the pressure in said main cylinder for preventing movement of said valve element past said intermediate position when released by said latch until the pressure in said main cylinder has dropped below a predetermined pressure, and then for releasing said valve element automatically for continued movement into said another position to cause retraction of said ram element, and manually controlled means operable in one direction to shift said valve element into said one position which is the latched position, and in another direction to release said latch.

7. In a fluid operated motor, a main cylinder, a pull-back cylinder, a ram element operated in opposite directions by fluid pressures in said cylinders, a source of operating fluid under pressure, a reciprocating operating valve having its movable valve element shiftable endwise into three different positions, connections between said source, said valve and said cylinder by which said valve connects said source to the main cylinder and the pull-back cylinder to exhaust whenever said valve element is in one position, by which the valve element connects said source to the pull-back cylinder and said main cylinder to exhaust while said valve element is in another of its positions, and by which the valve element cuts off escape of operating fluid from said pull-back cylinder and prevents delivery of fluid under pressure from said source to said main cylinder while said valve element is in an intermediate position, means urging said valve element yieldingly in a direction from said first to said another position, latch means for latching said valve element in said first position, means responsive to the pressure in said main cylinder and operable solely when the pressure in said main cylinder exceeds a predetermined pressure for operating said latch to release said valve element, means also responsive to the pressure in said main cylinder for preventing movement of said valve element past said intermediate position when released by said latch until the pressure in said main cylinder has dropped below a predetermined pressure, and then to release said valve element for continued movement into said another position to cause retraction of said ram element, a connection from said source to said latch releasing means and having a valve therein to control flow of fluid from said source to said latch releasing means, means operable by said ram element at a selected position in its forward travel under pressure from said main cylinder for operating said valve to direct fluid under pressure from said source directly to said latch releasing means and thus cause a retraction of said ram element, and means operable automatically to release the operating fluid under pressure delivered to said latch releasing means, when the flow of operating fluid under pressure to said latch releasing means is discontinued.

8. In a fluid actuated motor, a main cylinder, a pull-back cylinder, a ram element operated in opposite directions by fluid pressure applied alternately to said cylinders, a source of operating fluid under pressure, a controlling valve having a shiftable valve element, connections between said source and said cylinders and including said valve and effective when said valve element is in one position for directing operating fluid under pressure to said main cylinder and releasing the operating fluid from the pull-back

cylinder, effective for directing operating fluid under pressure to the pull-back cylinder and releasing fluid from the main cylinder when said valve element is in another position into which it may be moved, and effective to interrupt the delivery of operating fluid under pressure to the main cylinder when the valve element is in an intermediate position, a latch for releasably holding said valve element in said first position, means acting on said valve element for urging it from the first position into said another position, releasing means operable on said latch to release said valve element and controlled in parallel by the pressure in said main cylinder and the position of said ram element during a forward movement under pressure in said main cylinder, and operable to release said latch whenever the pressure on said main cylinder exceeds a predetermined pressure or the ram element reaches a predetermined and selected position in its movement under pressure from said main cylinder, whichever occurs first, and means also responsive to the pressure in said main cylinder during a forward movement of said ram element for blocking movement of said valve element, when the latter is released, beyond said intermediate position until the pressure on said main cylinder has fallen below a predetermined low pressure.

9. In a fluid actuated motor, a main cylinder, a pull-back cylinder, a ram element operated in opposite directions by fluid pressure applied alternately to said cylinders, a source of operating fluid under pressure, a controlling valve having a shiftable valve element, connections between said source and said cylinders and including said valve and effective when said valve element is in one position for directing operating fluid under pressure to said main cylinder and releasing the operating fluid from the pull-back cylinder, effective for directing operating fluid under pressure to the pull-back cylinder and releasing fluid from the main cylinder when said valve element is in another position into which it may be moved, and effective to interrupt the delivery of operating fluid under pressure to the main cylinder when the valve element is in an intermediate position, a latch for releasably holding said valve element in said first position, means acting on said valve element for urging it from the first position into said another position, releasing means operable on said latch to release said valve element and controlled in parallel by the pressure in said main cylinder and the position of said ram element during a forward movement under pressure in said main cylinder, and operable to release said latch whenever the pressure on said main cylinder exceeds a predetermined pressure or the ram element reaches a predetermined and selected position in its movement under pressure from said main cylinder, whichever occurs first, means also responsive to the pressure in said main cylinder during a forward movement of said ram element for forcibly blocking movement of said valve element, when the latter is released, beyond said intermediate position until the pressure on said main cylinder has fallen below a predetermined low pressure, fluid operated means connected to said source for forcing said valve element into said one position in which it is latched, valve means controlling said fluid operated means, and manually operated means also operable, when moved in one direction, on said valve element to shift it into latched position and when moved in

another direction for moving said latch to release said valve element.

10. In a fluid actuated motor, means including a hydraulic circuit for actuating said motor and having in said circuit a main controlling valve for controlling the operation of said motor, said valve having a valve element operable into different positions to regulate the activity of said motor, means for moving said element into one position into which it may be moved to cause movement of said motor in one direction, and including a controlling electric circuit, and a snap switch therefor having a switch member operable between "off" and "on" positions, in one of which it causes movement of said element into said one position and in the other of which it causes release of said element, said switch member being resiliently urged into "off" when moved one side of an intermediate position and into "on" position when moved in the other direction past said intermediate position, means yieldingly urging said element out of said one position and into a second position in which it stops further movement of said motor in the same direction, a hydraulic plunger directly responsive to the fluid pressure actuating said motor in said one direction and operable directly and mechanically upon said switch member to forcibly move it past said intermediate position towards said "open" position and cause release of said element when said pressure so actuating the motor exceeds a selected, predetermined pressure.

11. In a fluid operated motor, a main cylinder, a pull-back cylinder, a ram element operated in opposite directions by fluid pressures in said cylinders, a source of operating fluid under pressure, an operating valve having its movable valve element shiftable into three different positions, connections between said source, said valve and said cylinders by which said valve connects said source to the main cylinder and the pull-back cylinder to exhaust whenever said valve element is in one position, by which the valve element connects said source to the pull-back cylinder and said main cylinder to exhaust when said valve element is in another of its positions, and by which it cuts off escape of operating fluid from said pull-back cylinder and prevents delivery of fluid under pressure from said source to said main cylinder when said valve element is in an intermediate position, means yieldingly urging said valve element from said one position through said intermediate position into said another of its positions, means releasably holding said valve element in said one position, and a fluid actuated piston disposed in the path of movement of said valve element and operable when under pressure to prevent movement of said valve element under the action of said urging means beyond said intermediate position towards said another position, means including a cylinder for said piston and a connection from said piston cylinder to said main cylinder for applying to said piston the pressure of said main cylinder, whereby said valve element will be momentarily held in said intermediate position after release, until the pressure in the main cylinder has fallen below a predetermined pressure, and valve means in said last named connection and operable by said ram element to disconnect said piston cylinder from said main cylinder and connect it to the pull-back cylinder when the ram element reaches a predetermined retracted position.

12. In a fluid operated motor, a main cylinder, a pull-back cylinder, a ram element operated in

opposite directions by fluid pressures in said cylinders, a source of operating fluid under pressure, a main controlling valve having a casing and a movable valve element therein shiftable into three different positions, connections between said source, said valve casing and said cylinders by which said valve element in its movements connects the source to the main cylinder and the pull-back cylinder to exhaust when in one position, connects said source to the pull-back cylinder and said main cylinder to exhaust when in another position, and shuts off said pull-back cylinder from both said source and said exhaust, opens said main cylinder to exhaust and connects said source to exhaust when in an intermediate position, means yieldingly urging said valve element from said one position towards said another position, said valve casing having two separate chambers arranged in tandem at one end thereof, and said valve element extending piston-like into the first one of said chambers, a second piston disposed for endwise sliding movement in the wall between said chambers in the directions of movement of said valve element, opposing movement of said valve element, and having means limiting its movement in such opposing direction, a connection between the other of said chambers and said main cylinder by which the pressure on said main cylinder will be transmitted to said other of said chambers and will urge said piston in said opposing direction to limit the movement of said valve element beyond said intermediate position when the pressure on said main cylinder is above a predetermined pressure, a connection from said source to said one chamber for supplying thereto a fluid under pressure to shift said valve element into said one position, a valve in said last named connection for connecting said source to said one chamber or the latter to exhaust selectively.

13. In a hydraulic motor, a working member, a continuously operating pump, fluid actuated means including a main cylinder and a pull-back cylinder operable on said member to operate said member toward and from work, a reversing and controlling valve, a connection from said pump to said valve, connections from said valve to each of said cylinders, said valve having therein a valve element operable selectively into three positions, in one end position of which it connects said pump to the main cylinder and opens the connection to said pull-back cylinder to allow escape of operating fluid from that cylinder, and in another end position of which it connects said pump to said pull-back cylinder and opens the connection to said main cylinder to allow escape of operating fluid from that cylinder, and in an intermediate position of which it prevents escape of actuating fluid from said pull-back cylinder, releases the actuating fluid from said main cylinder and bypasses the fluid received in the valve from the pump, a choke in the connection from the pump to the valve for maintaining a predetermined, minimum back pressure on said pump, an auxiliary valve having a connection therefrom to said pump before said choke, so as to receive fluid under a minimum desired pressure continuously, hydraulic means controlled by said auxiliary valve and operable on said valve element to operate it into said one end position, means for urging said valve element into said another end position when said element is released by said hydraulic means, hydraulic means for forcibly moving said valve element into said intermediate position to stop the actuation of said member,

and means including a controlling valve connecting said last hydraulic means to said pull-back cylinder for operation by the fluid pressure in that cylinder, said valve being positioned for operation by said working member when the latter reaches a predetermined position in its return movement.

14. In a hydraulic motor, a working member, fluid actuated means including a continuously running pump, a main cylinder and a pull-back cylinder connected to said member for operating it toward and from work, a controlling valve connected to said fluid actuated means for causing an advance, a return or a stopping of said member and having a valve element operable into three positions, in one end position of which it causes delivery of actuating fluid to the main cylinder and opens the pull-back cylinder for escape of actuating fluid, and in another end position of which it connects the operating fluid to the pull-back cylinder and opens the main cyl-

inder for escape of operating fluid, and in an intermediate position of which it closes the pull-back cylinder against escape of actuating fluid, opens said main cylinder for the escape of actuating fluid and bypasses the fluid from said pump away from both cylinders, means for urging said valve element into said other end position, power means connected to said valve element for forcibly actuating the latter into said one position, a hydraulic device operable on said valve element to shift it from said other position into said intermediate position against the action of said urging means, and means controlled by said working member at a desired point in its return movement for connecting said pull-back cylinder to said hydraulic device and by the pressure of fluid from the pull-back cylinder operate said valve element into said intermediate position and hold it in that position after the valve element reaches said intermediate position.

THOMAS F. STACY.
